The ornamental design for an auxiliary sheet feeder for an inkjet printer, as shown and described.

DESCRIPTION

FIG. 1 is a perspective view of an auxiliary sheet feeder for an inkjet printer in accordance with the present invention;

FIG. 2 is a top plan view thereof;

FIG. 3 is a front elevational view thereof;

FIG. 4 is a left side elevational view thereof;

FIG. 5 is a rear elevational view thereof;

FIG. 6 is a right side elevational view thereof; and,

FIG. 7 is a bottom plan view thereof.

The broken line showing of a potential electrical interconnect plug in FIGS. 1—6, and of potential alignment pins for coupling the auxiliary sheet feeder with an inkjet printer in FIGS. 1—6, is for illustrative purposes only and forms no part of the claimed design.
